United States Patent Office

Des. 198,311
Patented June 2, 1964

198,311

AUTOMOBILE

Karl Wilfert, Gerlingen-Waldstadt, and Béla Barényi,
Stuttgart-Vaihingen, Germany, assignors to Daimler-
Benz Aktiengesellschaft, Stuttgart-Untertuerkheim,
Germany

Filed Sept. 13, 1963, Ser. No. 76,589

Claims priority, application Germany Mar. 13, 1963

Term of patent 7 years

(Cl. D14—3)

The essential features of the design reside in the parts shown in full lines.

We claim:

The ornamental design for an automobile, as shown and described.
